Attorney.

UNITED STATES PATENT OFFICE.

EDWARD A. MOORE, OF CHICAGO, ILLINOIS, ASSIGNOR TO R. F. SIMMONS COMPANY, A CORPORATION OF RHODE ISLAND.

CHAIN.

1,190,446.

Specification of Letters Patent. Patented July 11, 1916.

Application filed April 7, 1916. Serial No. 39,589.

To all whom it may concern:

Be it known that I, EDWARD A. MOORE, a citizen of the United States, residing at Chicago, in the county of Cook and State 5 of Illinois, have invented certain new and useful Improvements in Chains, of which the following is a specification.

My invention relates to an attachment or accessory for use with various kinds of 10 chains among which are Waldemar chains. This type of chain stretches between opposite vest pockets, and is not provided with any center bar or any center piece or tripod, and has no means for securing the chain 15 at any point intermediate its length; its only engagement being at its ends with a watch and pencil, knife, or other article.

The essential objects of my invention are 20 to furnish an intermediate guide and support for the chain; to insure the chain and its connected article against theft or accidental escape; to permit the use of the chain as a double chain; to enable the wearer to utilize the entire length of the chain by 25 detachment whereby a maximum of freedom is afforded for manipulating the knife, pencil or other article connected therewith; to afford a means of chain support adapted to facile, universal, and secure engagement 30 with the clothing of the wearer; to permit instantaneous engagement and disengagement of the chain, and without removing the device from the garment, and to attain these ends in a simple and inexpensive structure.

To the above ends essentially my invention consists in such parts and combinations of parts as fall within the scope of the appended claims.

40 In the accompanying drawings which form a part of this specification, Figure 1 is a front elevation of a chain in engagement with the support attached to a vest, Fig. 2, an enlarged front elevation of the 45 support, Fig. 3, a section of the same on line 3—3 of Fig. 1, and Fig. 4, a rear elevation of the same.

Like reference characters indicate like parts throughout the views.

50 In the drawings 6 are the button holes, 7 the buttons, and 8 and 9 the opposite pockets of a vest 10.

11 is the attaching ring of a knife, pencil, or other article in the pocket 8; and

13, the suspension ring of a watch 14 in 55 the pocket 9.

A vest chain 16 provided with end rings or swivels 17 and 18 is shown engaged with the rings 11 and 13 respectively. Loosely engaging this chain is an attachment, guide, or support represented in a general manner by the numeral 20. This member comprises parallel front and back plates 21 and 22 respectively connected at their ends by a hook 23, the whole forming a U-shaped 60 frame. To the lower or free end of the plate 21 is a resilient arm 24 extending below the plane of the walls as at 25 where the arm has an open loop or vertically disposed bend 26 and thence extends upwardly 65 in front of the plate 21, and is then curved inwardly and downwardly as at 28 until it is adjacent to or in contact with the plate 21, as at 29. In the present instance there is a space 30 between the arm and the front 70 plate at this point. Thence the arm extends downwardly and outwardly, as at 31 completing a circular hook upon the upper end of the arm 24. At the junction of the front plate and the arm is preferably an 75 external shoulder 32.

Soldered or otherwise fixed in the frame in the present instance is a lining plate 33 having surface prong or prongs 34 on one portion, and an opening 35 in its opposite 80 portion. The wall 22 has also an opening 36 at this point to accommodate a cam 37 which co-operates with the prong or prongs 34, when any prong is present. Integral with the cam is a lever arm 38 pivoted by 85 lateral pins 39 in seats 40 in the plate 22. The lever arm is vertical in the opening 36 when the parts are in closed or clamping position as shown in Fig. 3, but is manually oscillated rearwardly and downwardly to 90 bring the cam out of engagement with any fabric between the prongs and cam.

The member 20 is inserted into a button hole 6 with the plates 21 and 22 against the front and back surfaces of the vest respectively, and with the yoke resting upon the fabric forming the bottom edge of the button hole. In this position the frame is clamped by manipulating the lever 38.

The chain 16 rests in the loop 26 of the 105 arm 24 and is of greater diameter than the passage 30, so that it will not accidentally escape therethrough. When, however, it is

desired to disengage the chain from the retaining device, as for enabling a free use of the knife or pencil, the chain is manually elevated by raising the knife from the pocket 8 and this movement brings the chain into contact with the curved guiding surface 31 of the hook and forces the resilient arm 24 outwardly, permitting the escape of the chain through the passage 30. To reengage the chain it is downwardly pressed against the curved surface 28 which guides it through the passage 30 into its original or engaged position.

When it is desired to convert the chain into a double chain, the ring or swivel 17 is disengaged from the ring 11 and that end of the chain is folded back and attached to the ring 13.

I claim:

1. In a device of the character described, a frame comprising a yoke, a front plate, and a back plate, and an arm upon the lower portion of the front plate extending outwardly and upwardly adapted to embrace a chain and terminating adjacent the front plate.

2. In a device of the character described, a frame comprising a yoke, a front plate, and a back plate, an upright resilient arm upon the end of the front plate provided with an arcuate bend adjacent its connection with the front plate and adapted to engage a chain, and a curved guiding member upon the free end of the arm adjacent an intermediate portion of the front plate.

3. In a device of the character described, a frame comprising a yoke, a front plate,

and a back plate, a resilient arm upon the free end of the front plate extending downwardly, outwardly and upwardly adapted to embrace a chain, and a circular hook upon the free end of the arm spaced from an intermediate portion of the plate a less distance than the thickness of the chain.

4. As an improved article of manufacture 45 a safety attachment for chains, comprising a front plate, a back plate, a yoke connecting the plates at one end, a clamping member in one of the plates, a resilient arm integral with the free end of the front plate provided with a loop extending below the plane 50 of the front plate, and a hook upon the free end of the arm adjacent an intermediate portion of the front plate.

5. A safety attachment for chains, comprising a back plate and a front plate with oppositely disposed bends and a free arm 55 extending from the bend of the front plate with its free end curved inwardly toward the front plate and formed into a curved 60 hook.

6. A safety attachment for chains, comprising a back plate and a front plate with oppositely disposed bends and a free arm 65 extending from the bend of the front plate with its free end curved inwardly toward the front plate and formed into a curved hook, and means pivoted in the back plate and operable between the back and front plates to clamp a fabric therebetween.

In testimony whereof I have affixed my signature.

EDWARD A. MOORE.
